UNITED STATES PATENT OFFICE

2,440,491

OIL BURNER

Erwin Frédéric Schwander, Reichshoffen, France,
assignor to Societe d'Etudes des Véhicules "Sev,"
Reichshoffen (Bas-Rhin), France, a society of
France

Application February 20, 1936, Serial No. 64,928
In France March 21, 1935

Section 3, Public Law 690, August 8, 1946
Patent expires March 21, 1955

1 Claim. (Cl. 158—73)

1

This invention relates to an oil burner, particularly for steam generators for vehicles. It is known that these burners, by reason of the relatively small dimensions of the furnace, must produce a flame which, while being as short as possible, fills, to a major extent, the generally cylindrical or cubical chamber of the furnace in such a way as to permit a very concentrated working thereof.

In order that the flame shall not be extended too much, it is necessary that the fuel should be finely pulverised, and this is only possible by using a pulverisation by means of compressed air or steam or by supplying the oil under pressure. Neither the method of realising such a pulverisation nor that of realising a correct proportioning of the amount of fuel and air as a function of the conditions of combustion adopted in every case forms the subject of the present invention which only relates to the particular construction of the burner so that an intimate mixture of the fuel and of the air is ensured while the flame is guided so as to respond to the requirements set forth.

The attached drawing shows by way of example two embodiments of oil burners according to the invention.

Fig. 1 is a longitudinal section of the first embodiment in which the paths of the fuel and air are indicated by parallel lines;

Fig. 2 is a similar section of the same embodiment showing the different zones of combustion;

Fig. 3 is a longitudinal section of the second embodiment.

Fig. 1 shows an axial section of the burner in position relatively to the furnace of the steam generator. The chamber shown in dotted lines is the furnace chamber of which the walls may be constituted by tubular heating surfaces and which preferably have a transverse circular section.

The burner is composed of the body *a* with an air inlet tube *b* and a combustion mouth *c*. At the centre of the body but separated from its end is placed a cup-like part *d* pierced at its base with slots or apertures. The total section of these apertures is such that 10 to 25% of the total volume of air can pass therethrough. The oil nozzle *e*, which could be of the open or closed type, opens into the centre of the base of the cup *d*. Also, a baffle plate *f* is disposed at a certain distance in front of the mouth *c* of the body of the burner *a* and perpendicular to the axis of the burner. This plate is supported in any suitable way, for example by the construction of the generator or of

the burner. Ignition is performed by an electric sparking device placed either inside or immediately to the outside of the cup *d*. The electrodes against which the sparks impinge are not shown.

5 The operation of the burner is shown on Figs. 2 and 3 and is as follows:

The secondary air current *1* flows all around the cup *d* while the current of primary air *2* constituting 10 to 25% of the former passes into the 10 cup itself where it is charged with particles of fuel. The former encloses the second up to a point in front of the baffle plate *f* which, by reason of the different displacements of the air currents, produces an intimate mixture thereof. The 15 shaded part of Fig. 2 shows the mixing zone.

Fig. 3 shows the formation of the flame itself. It will be noted that only in the exterior zone of the primary air current charged with fuel there is produced a combustion immediately after the 20 ignition. Towards the interior of the said current, on the contrary, the particles of fuel cannot burn owing to lack of air. They are, however, gasified by the heat radiated by the exterior burning envelope. In the mixture zone shown on Fig.

25 2, these three constituents are mixed intimately, that is the air in the secondary air current, the flames of the burning envelope of the primary current and the remainder of the gasified carburant. As a substantial portion of the fuel is 30 in gasified form, a perfect combustion is obtained with a short flame. At the same time the flame is spread out as a dovetail by the baffle plate *f* and has a form completely filling the furnace. It will be noted that after leaving the nozzle, no part 35 of liquid fuel comes into contact with metal.

As will be seen from Figs. 2 and 3, the burner is not likely to heat up, since all its metallic parts are cooled by air. In the same way, the baffle plate is cooled in an effective manner so that 40 it can be formed of cast material without inconvenience.

Of course, other materials could also be utilised, in particular metallic alloys which are resistant to heat, ceramic materials or the like.

45 Instead of employing a simple baffle plate, one could also employ, as shown on Fig. 3, a head *f*¹ provided with air ejection nozzles *l*. These nozzles supply air directly contrary to or obliquely to the jet leaving the burner. The air is supplied to 50 the head *f*¹ by means of a side branch in the air inlet to the burner, as indicated in Fig. 3, dotted lines between these two figures showing the air path to the head *f*¹. The whole of the combustion air is thus divided into three currents, the secondary current *1*, primary air *2* and tertiary air

3. A very favourable combustion is obtained if the tertiary current 3 is preheated.

I claim:

In an oil burner particularly for steam generators for vehicles comprising in combination a tubular burner body receiving combustion air, a sleeve-like member in the body for dividing the combustion air into a primary and a secondary air current, an oil nozzle and an electric ignition device in said member and a baffle plate disposed in front of the tubular body, the sleeve-like member being a cylindrical cup having a perforated bottom turned against the air current, said tubular body extending beyond the cup mouth and the inner walls thereof being throughout their whole length essentially parallel to those of the cup.
